UNITED STATES PATENT OFFICE.

JOHN H. MICHENER, JR., OF NEW YORK, N. Y., ASSIGNOR TO MICHENER STOWAGE COMPANY, OF NEW YORK, N. Y., A CORPORATION OF NEW YORK.

ELEVATOR.

1,010,297.

Specification of Letters Patent. Patented Nov. 28, 1911.

Application filed September 4, 1909. Serial No. 516,291.

To all whom it may concern:

Be it known that I, JOHN H. MICHENER, Jr., a citizen of the United States, and a resident of New York, in the county of New York and State of New York, have invented certain new and useful Improvements in Elevators, of which the following is a specification.

This invention relates to elevators and particularly to that class thereof, portable or otherwise comprising blades or buckets on an endless carrier adapted for raising bulk material such as coal, grain and the like.

The present invention has been developed particularly with reference to adaptability to raising coal from barges to the coaling ports of ships but it is obvious that it is equally adapted for handling a large variety of bulk material and while I have illustrated and described my improvements in their particular adaptability to the handling of coal I do not restrict my invention to such narrow use.

The object of my improvements is to furnish means simple in construction and action, mobile in adaptability and efficient in use for raising and discharging bulk material.

In the drawings accompanying this specification I have illustrated one embodiment and which may be the preferred embodiment of my improvements. Therein Figure 1 is a sectional side elevation of my apparatus with the telescopic member retracted. Fig. 2 is a similar view to that of Fig. 1 but with the telescopic member extended. Fig. 3 is a side elevation on an enlarged scale of the upper end of my apparatus. Fig. 4 is a sectional side elevation on the same scale as Fig. 3, of the lower end of my apparatus. Fig. 5 is a rear side view of a detail, on a still larger scale, of a locking device for the telescopic member. Fig. 6 is an end view corresponding with Fig. 5. Fig. 7 is a cross sectional view on line 7, 7 of Fig. 4. Fig. 8 is an end elevation corresponding with Fig. 4. Fig. 9 is a sectional side elevation, on line 9, 9 of Fig. 10 on the scale of Fig. 3 of the upper end of my apparatus. Fig. 10 is a cross sectional view on line 10, 10 of Figs. 3 and 9. Fig. 11 is a side elevation to a reduced scale illustrating my apparatus in use lifting coal from a barge and discharging it into the coal port of a ship. Fig. 12 is a rear elevation illustrating means for operat-

ing the several mechanisms of my apparatus. Figs. 13, 14, 15 are detail side views similar to a portion of Fig. 11 illustrating successive steps of one feature of the operation of my improved apparatus.

My improvements comprise in general a main member 2, a telescopic member 3 slidable therein, an endless chain 4 carrying buckets 6, said chain being supported on sheaves or sprockets 80, 90, 10 and 11 in main frame 2 and 12, 13 in telescopic member 3. Said sheaves of main frame 2 and telescopic member 3 are so located relative to each other as to maintain an even length or tension on chain 4 irrespective of the relative positions of said members 2, 3. Power for driving the apparatus is preferably installed in the upper part of main member 2 and may comprise a motor 15 or other suitable means. Electric wires 32 from some suitable source of power, not shown, lead to starting box 33 conveniently located on the outside of frame 2 (Fig. 11). From this starting box wires, not shown, may lead to said motor 15. Motor 15 is illustrated as provided with worm 16 engaging worm gear 17 on cross shaft 19 (see Figs. 1, 2, 9 and 10). On the outboard left hand end (Fig. 10) of shaft 19 is loosely mounted, sprocket 20. Said sprocket is connected to and drives sprocket 21 through chain 22. Sprocket 20 has clutch member 201 formed thereon for engagement with clutch member 202 slidably mounted on shaft 19 and key 190 therein (Fig. 3). Clutch member 202 may be thrown into and out of engagement with sprocket clutch member 201 by means of a suitable lever not shown, through rod 24 and bell crank yoke 25.

Referring now more in detail to the construction of my apparatus, while in my general description I have mentioned only one endless chain 4, I preferably use two such chains 4 and 5 between which I support blades or buckets 6, (Figs. 7 and 8). While said blades 6 may be of any one of a variety of cross sections I preferably bend their edges forward in the direction of their travel, Fig. 4, to increase their carrying capacity.

Main member 2 is of rectangular boxlike form having a lower open end for the free movement in and out thereof of telescopic member 3. At its upper end main member 2 has an overhanging portion 200 in which

105

110

is supported shaft 801 carrying sprockets 8 and 80 for chains 5 and 4 respectively. Said overhanging portion 200 also provides discharge port 203 for the material lifted by 5 blades 6. Said main member 2 has rails 26 (Fig. 7) for guiding engagement with rolls 27 of telescopic member 3, and rolls 28 at its lower end for guiding engagement with frames 30 of said telescopic member 3. By 10 these means said telescopic member is suitably supported for free in and out movement in main frame 2. The several sheaves of main member 2 and of telescopic member 3 are relatively so arranged as to maintain the 15 principal runs of chain as 40, 41, 42, 43 of chain 4 always in parallelism. Also the axes of the sheaves of main member 2 being fixed relative to each other and the axes of the sheaves of the telescopic member 3 being 20 fixed relative to each other, and said telescopic member being slideable in parallelism with said principal runs of chain it follows that in all positions of the telescopic member 3 relative to main member 2, from the 25 inward position of Fig. 1 to the outward position of Fig. 2 chains 4 and 5 will be maintained at uniform tension and in operable position on their several sprockets. Telescopic member 3 is provided with a floor 30 or pan 31 over which the coal is scraped upwardly onto floor 210 of main member 2 and thence upwardly and out through port 203. Sheaves 13, 14 at the lower end of telescopic member 3 are supported on inreaching studs 35 130, 140 respectively so as to allow freedom for coal therebetween. Said sheaves are provided with toothed disks 131, 141 respectively for loosening up the mass of coal to allow freer access of blades 6 thereto.

40 For lifting telescopic member 3 from its outward position (Fig. 2) to its inward position (Fig. 1) I employ the following means. Pivoted at 34 in member 3 (Fig. 4) is shoe 35 for engagement with the upper 45 face of lower run 43 of chain 4. The lower face of said run 43 rides on guide 16. Cam lock 37 is pivoted at 36 in member 3 above said shoe 35 and is operable by means of lever 38 thereon to clamp run 43 of chain 4 50 between shoe 35 and guide 16. When so clamped, run 43 of chain 4 in its upward movement carries telescopic member 3 therewith. Upon releasing lever 38 cam 37 is returned to its inoperative position by means 55 of spring 39 of arm 93 of said lever 38. For holding said telescopic member 3 against outward movement relative to member 2, from the position for instance of Fig. 1 to that of Fig. 2, I provide an automatic 60 catch shown in detail in Figs. 5 and 6, and more fully in relation to said frames 2 and 3 in Fig. 4. Therein toggle arms 62, 63 are pivoted at 620, 630 respectively in nose 64 of frame 2. The free ends of said toggle 65 arms 62, 63 are positioned and adapted for

engagement with upper and lower side rails 30, 30 of telescopic member 3. Said arms 62, 63 are urged to engagement with said rails 30, 30 by means of spring 67 in coaction with rods 68, 69 pivotally connected 70 with said arms. Arms 62, 63 may be moved to their inoperative positions, shown in dotted lines in Fig. 5 by means of cam 75 pivoted coaxially with rod 69 in arm 62. For operating said cam 75 hand lever 79 is provided. 75

In case the coal is not taken away within the ship (Fig. 11) with sufficient rapidity it sometimes happens that said coal is congested at the mouth or port 203 of member 2. 80 To provide for this contingency I furnish table 81 extending entirely across within member 2 and having end 82 thereof reaching around shaft 801 of sprockets 8 and 80. Said table is slotted at 84, 85 to admit said sprockets. At 83 said table reaches around sprocket shaft 92.

For conveniently handling and adjusting my improved apparatus I have provided several devices which I will now proceed to 90 describe. For hoisting the apparatus into position I have mounted a winding drum 50 on shaft 51 in the upper part of member 2 and parallel with worm gear shaft 19. On said shaft 19 is loosely mounted sprocket 56 having clutch member 57 thereof for engagement with clutch member 58 slidably mounted on shaft 19 and key 59 thereof. Shaft 51 has sprocket 52 fixed thereon and is connected to and driven from sprocket 56 by chain 54. Clutch member 58 on shaft 19 may be operated in the usual way by lever mechanism indicated in a general way by 60. To prevent rotation of drum 50, when clutch 57, 58 is disengaged, I provide ratchet 76 fixed on shaft 51 and pawl 77 pivotally mounted on bracket 78 of frame 2 for engagement with said ratchet. Drum 50 is provided with friction clutch mechanism indicated at 53, slidably mounted on shaft 51 and key 55 therein. Said friction clutch mechanism may be operated in the usual way by lever mechanism indicated in a general way by 65. The operating levers of mechanism 60 and 65 are located on the outside of frame 2 conveniently near the starting box 33 of motor 15. Rope 45 of winding drum 50 passes out of frame 2 through slot 44 (Fig. 10) and thence over suitable blocks as 46 (Fig. 11) one of which, not shown, is 100 fastened at a proper height to ship 100. Concentric with drum shaft 51 and at each side of frame 2, I pivotally attach arms 47, 48 of bail 478. Said bail by means of double ended hook 49 may be attached to 105 some convenient eye as 61 of ship 100. To hold off head end 200 of frame 2 from ship 100 I provide a pair of struts as 66 preferably A shaped having two feet 660, 660 for engagement with the ship's side. Said struts 110

are preferably pivotally mounted on frame 2 concentric with shaft 51, and are provided with clamping means as 606 for holding them against turning. To hold lower end 5 of frame 2 from ship 100 I provide strut 70 supported in box 74 pivoted on axial shaft 720 of pinion 72 on the side of frame 2 (Fig. 11). Said strut 70 is provided with teeth 71 for engagement with the teeth of 10 pinion 72. Said pinion may be actuated by the usual crank 73. Said crank is provided with a stop pin 740 for engagement with block 74 to hold said crank against turning after strut 70 has been set in a desired position. 15 Strut 70 when not engaged may be removed or folded up against the side of frame 2. A chute 86 pivotally supported on the projecting ends of shaft 801 may be provided to lead the coal from port 203 of member 2 to hopper 101 of ship 100.

The operation of my improved mechanism is as follows: Assuming the machine to be lying on its back with overhanging portion 200 pointing upwardly and with 25 telescopic member 3 retracted, block 46 is hooked into the eye provided therefor and rope 45 attached to drum 50 (Figs. 10 and 11). Clutch member 202 being out of engagement with clutch member 201, clutch 30 member 58 being in engagement with clutch member 57, and clutch 53 being in engagement, motor 15 is started. This, through worm and gear 16, 17 respectively, sprocket 56, chain 54 and sprocket 52, drives shaft 35 51 and drum 50 thereon. Whereupon rope 45 is wound onto said drum and the head end of the machine lifted until hook 49, one end of which is engaged with eye 61 on ship 100, is hooked into bail 478. Motor 15 is 40 now stopped and struts 66, 66 adjusted against the ship's side. Then clutch 53 is disengaged, rope 45 slackened and the weight of the machine sustained by hook 49. Clutch 53 may now be returned to engagement 45 and clutch 57, 58 released from engagement preparatory to starting conveyer chains. The machine is then free to swing pivotally about shaft 51 as an axis. Strut 70 is then adjusted against the ship's side 50 and by means of crank 73, pinion 72 and rack teeth 71, the lower end of the machine is swung outwardly in position over the hatchway 87 of coal barge 88. Thereupon hand lever 79 is moved toward its dotted 55 position (Fig. 5) and telescopic member 3 is allowed to descend for engagement with the coal in barge 88 (Fig. 11). By proper manipulation of said lever 79 governing toggle arms 62, 63, member 3 may be kept 60 under full control and lowered as slowly as desired. When said telescopic member 3 has been lowered to its working position I preferably throw lever 79 fully to its dotted position (Fig. 5) whereby toggle arms 62, 65 63 are held in inoperative position. Clutch

202, 201 is thrown into engagement and motor 15 started. Whereupon through sprocket 20, chain 22 and sprocket 21, chains 4, 5 and buckets 6, 6 therebetween are started moving in the direction of their several arrows. 70 Also toothed disks 131, 141 are caused to revolve and loosen up the coal which is thereupon scraped upwardly by buckets 6, 6, onto bottom 31 of telescopic member 3 and thence onto bottom 210 of main member 2 and thus outward through 75 port 203 of overhanging portion 200. The coal then falls through chute 86 into hopper 101 and thence through the ship's port hole to the bunker. As the coal is removed from 80 the barge by the machine telescopic member 3 automatically sinks its nose by gravity deeper and deeper into the coal in the barge thereby 85 always working at high efficiency. Also while said telescopic member 3 is thus moving outwardly from main member 2, chains 4, 5 constantly maintain their working relation to their supporting sprockets and are kept constantly at a uniform tension by my improved arrangement, fully described 90 above herein. When telescopic member 3 has dug its way to the bottom of the barge or to the extent of its travel, toggle arms 62, 63 are thrown into their operative positions by means of lever 79 and lever 38 is 95 operated to cause cam 37 to press shoe 35 against run 43 of the conveyer chain; said chain is thereby clamped to member 3 and which member is thereupon retracted by 100 said chain to any desired height. Lever 38 is thereupon released, chain run 43 freed and member 3 is prevented from falling by toggle arms 62, 63. Barge 88 may now be shifted lengthwise or my machine shifted crosswise, by means of strut 70, to present 105 a fresh portion of the coal pile. Toggle arms 62, 63 are thereupon released and member 3 is lowered to its work. Lever 79 is thereupon thrown fully to its dotted position of Fig. 5.

A highly useful and novel feature of my improved apparatus is its ability to automatically retract member 3 when overloaded or congested. It frequently happens that when said member 3 has dug its way downwardly into the coal pile that the walls of the cavity thus made cave in and precipitate a mass of coal onto and about the lower end of said member. This immediately causes more or less congestion at said lower end, particularly where chains 4, 5 pass onto sheaves 13, 14, or tends to jam the entrance where the conveyer blades enter over floor 31. This jamming acts exactly as does clamping shoe 35 and causes the conveyer 115 to pick up said member 3 and lift it free of the congestion, whereupon, toggle arms 62, 63 being in inoperative position, telescopic member 3 slides downwardly and blades 6, 6 proceed upwardly with their loads. 120 125 130

Another phase of the automatic retracting feature of my improved apparatus is shown in Figs. 13, 14 and 15. In Fig. 13 the telescopic member is shown with its 5 lower end more deeply immersed in the coal pile than shown, for instance, in Fig. 11, and with that portion of the coal at 120 caved in about said telescopic member, whereby bucket 600 is hindered or stopped 10 in its downward movement. If the resistance to the downward movement of bucket 600 is greater than the weight of the telescopic member the upward pull of run 400 of the conveyer chain will lift said telescopic member 3 bodily and said bucket 600 15 will remain fixed in the coal pile until said bucket is turned about sprocket 13, Fig. 14 and thereby freed from said coal pile to pass upwardly with run 400 of the conveyer 20 chain. Then if the caved in portion 120 be of sufficient height the succeeding buckets 601, 602 will successively engage the coal pile as wall 250 withdraws upwardly with telescopic member 3 thereby allowing the 25 coal to fall about said buckets, Fig. 14. Said telescopic member 3 then continuing its upward movement, will turn buckets 601, 602 about sprocket 13 until it frees itself 30 fully from said coal pile, Fig. 15 and will then again proceed to dig its way downwardly. If desired, at the time said telescopic member starts to retract from the caved in coal pile, lever 79 may be thrown from its dotted line position to its full line 35 position, Fig. 5, and said telescopic member will therefore be automatically prevented from returning downwardly after having freed itself from the pile, Fig. 15, until the operator chooses to release it for 40 such downward movement. The successive positions of the telescopic member relative to the congested blades, as 600, 601, 602 and 603, may be easily read against horizontal guide line A A. Said automatic re- 45 tracting ability of my improved apparatus is due to the fact that said telescopic member is mounted to slide upwardly in the main member without encumbrance and therefore follows the path of least resist- 50 ance when an obstruction occurs.

When the barge has been unloaded toggle arms 62, 63 are thrown into operative positions, clamp shoe 35 thrown into action and member 3 retracted to its inward position. 55 Motor 15 is then stopped, clutch 201, 202 disengaged, clutch 57, 58 thrown into engagement and the motor again started. This causes rope 45 to be wound onto drum 50 thus hoisting the machine free of hook 49. 60 Strut 70 may then be removed and the machine lowered and stowed for future use.

I claim:

1. A portable elevator comprising a main member, a telescopic member slidable there- 65 in, an endless conveyer supported for move-

ment within the main member and the telescopic member, means for actuating the conveyer and means for causing said conveyer to retract the telescopic member within the main member. 70

2. A portable elevator including in combination, a main member, a telescopic member slidable therein, an endless conveyer supported for movement within the main member and the telescopic member, automatic means for preventing outward movement of the telescopic member relative to the main member and means for engaging and disengaging said automatic means for preventing outward movement. 75 80

3. A portable elevator comprising a main member, a telescopic member slidable therein, an endless conveyer supported for movement within the main member and the telescopic member, means for actuating the conveyer and means for locking the conveyer to the telescopic member for retracting said telescopic member within said main member. 85

4. A portable elevator comprising a main member, a telescopic member slidable therein, an endless conveyer supported within the main member and the telescopic member, means for actuating the conveyer, means for retracting the telescopic member and automatic means for preventing outward movement of the telescopic member relative to the main member. 90 95

5. A portable elevator comprising a main member, a telescopic member slidable therein, an endless conveyer supported within the main member and the telescopic member, means for actuating the conveyer and automatic means for preventing outward movement of the telescopic member relative to the main member. 100 105

6. A portable elevator including in combination, a main member, a telescopic member slidable therein, an endless conveyer having blades thereon, supported for movement within the main member and the telescopic member, means carried by the telescopic member for automatically maintaining said conveyer at uniform tension, said telescopic member mounted for free upward movement in said main member to permit said telescopic member to retract automatically when a downwardly moving blade therein encounters a resistance in excess of the weight of said telescopic member, automatic means for preventing outward movement of said telescopic member relative to said main member when said downwardly moving blade is freed from said excess resistance and means for actuating the conveyer. 110 115 120

7. A portable elevator including in combination, a main member, a telescopic member slidable therein, an endless conveyer having blades thereon, supported for movement within the main member and the telescopic member, means carried by the telescopic 125 130

member for automatically maintaining said conveyer at uniform tension, said telescopic member mounted for free upward movement in said main member to permit said telescopic member to retract automatically when a downwardly moving blade therein encounters a resistance in excess of the weight of said telescopic member, automatic means for preventing outward movement of said telescopic member relative to said main member when said downwardly moving blade is freed from said excess resistance, means for engaging and disengaging said automatic means for preventing said outward movement and means for actuating the conveyer.

8. A portable elevator comprising a main member, a telescopic member slidable therein, an endless conveyer comprising four parallel runs supported on sprockets revolubly fixed in opposite ends of said telescopic member and on other sprockets revolubly fixed in opposite ends of the main member,

manually operable means on the telescopic member for locking said conveyer to said telescopic member for retracting the telescopic member and means for actuating the conveyer.

9. A portable elevator comprising a main member, a telescopic member slidable therein, an endless conveyer comprising four parallel runs supported on sprockets revolubly fixed in opposite ends of said telescopic member and on other sprockets revolubly fixed in opposite ends of the main member, means for gripping the conveyer to the telescopic member for retracting the telescopic member and means for actuating the conveyer.

Signed this 13th day of August 1909 before two subscribing witnesses.
